UNITED STATES PATENT OFFICE.

FRANK A. HOLLENBECK, OF SYRACUSE, NEW YORK.

DESIGN FOR A BICYCLE-SADDLE FRAME.

SPECIFICATION forming part of Design No. 28,433, dated March 29, 1898.

Application filed January 24, 1898. Serial No. 667,833. Term of patent 7 years.

To all whom it may concern:

Be it known that I, FRANK A. HOLLENBECK, a citizen of the United States, residing at Syracuse, in the county of Onondaga and State of New York, have invented and produced a new and original Design for a Frame of a Bicycle-Saddle; and I do hereby declare the following to be a full, clear, and exact description of the same, reference being had to the accompanying drawings, forming a part thereof.

My invention is a new and original design for the frame of a bicycle-saddle; and it consists in the form and contour illustrated in the accompanying drawings and fully disclosed in the following description and claim.

Referring to the said drawings, Figure 1 represents a top plan view of a frame-plate of a bicycle-saddle embodying my design. Fig. 2 is a transverse sectional view of the same on line 2 2 of Fig. 1. Fig. 3 is a sectional view on line 3 3 of Fig. 1. Fig. 4 is a central longitudinal sectional view.

The saddle-frame has a back edge *a* curved outwardly in an arc of a circle, each end of the arc being curved sharply inward at *b* to a point near the center and then curving forward at *c* in a direction inclined to the longitudinal axis of the plate to form a short narrow projecting part *d*, which has a rounded end. Entirely surrounding the edge of the plate is a downwardly-extending inclined

flange *e*. A longitudinal groove *f* extends from a point near the back edge *a* to the point of the projection *d*. The outer edges *g g* of the plate are higher than the central portions *h h* of the plate adjacent to the groove *f* and the portions *k k* of the plate between said groove and said edges *g g* are depressed, as shown in Fig. 2. The back edge *a* is also higher than the front edges *b*, as shown in Fig. 3.

The foregoing constitute the leading features of my design.

The portions *h h* of the plate adjacent to the groove extend from the rear part of the plate upwardly, as shown at *l*, for a short distance and then extend forwardly, as at *m*, to the point of the projection.

The portions *k k* of the plate between the back edge *a*, the groove *f*, and the front edge *b* are dotted with perforations *n*, and a row *o* of perforations *o* extends longitudinally through the groove *f*.

What I claim, and desire to secure by Letters Patent, is—

The design for the frame of a bicycle-saddle, substantially as shown and described.

In testimony whereof I affix my signature in presence of two witnesses.

FRANK A. HOLLENBECK.
